UNITED STATES PATENT OFFICE

JOHN B. KOHLER, OF CHICAGO, ILLINOIS, ASSIGNOR TO G. A. EDWARD KOHLER, OF CHICAGO, ILLINOIS

PAPER DELIVERING DEVICE

Application filed March 7, 1929. Serial No. 345,172.

This invention relates to paper delivering devices and has for its object to provide a new and improved device of this description.

The invention has as a further object to provide a device for supplying paper to printing presses, bag machines and the like wherein paper is supplied continuously from successive rolls of paper, the end of the web of the new roll being connected with the web of the exhausting roll without stopping the press or other machine to which the paper is supplied and wherein the new roll is brought up to the desired speed by the same mechanism used in delivering the paper to the press and the end of the web of the new roll connected to the web of the exhausted roll while the press or other machine is running at high speed.

The invention has as a further object to provide a mechanism which will connect the web of a new roll to the web of the exhausted roll while the machine to which the paper is being delivered is run at high speed.

The invention has other objects which are more particularly pointed out in the accompanying description.

Referring now to the drawings, Fig. 1 is a side elevation of one form of device embodying the invention showing the paper as being delivered from a full roll.

Fig. 2 is a view similar to Fig. 1 when the parts are in position to connect the web of the new roll with the web of the exhausted roll, with the motor and gearing removed.

Fig. 3 is an enlarged view showing the end of the web of the new roll as it is about to be connected with the web of the exhausted roll.

Fig. 4 is an enlarged, sectional view taken on line 4—4 of Fig. 1.

Fig. 5 is an enlarged view of the holding releasing mechanism for the new roll.

Fig. 6 is an enlarged sectional view taken on line 6—6 of Fig. 5.

Fig. 7 is an enlarged sectional view taken on line 7—7 of Fig. 5.

Like numerals refer to like parts throughout the several figures.

The drawings show one form of device em-

bodying the invention. In this construction there is a paper roll supporting device consisting of a movable or rotatable member carrying a plurality of rolls of paper and arranged so that a new roll may be brought into operative position when the preceding roll is about exhausted. For purposes of illustration, there is shown a device of this kind consisting of a rotatable shaft 1 which is provided with a plurality of arms 2 arranged in pairs spaced apart along the shaft, the rolls of paper 3, 4, and 5 being rotatably mounted between these arms.

One or more roll engaging devices 6 are provided which engage the web of the paper on the roll from which paper is being delivered to the device in connection with which it is used. This roll engaging device assists in the operation of delivering the paper to the device which uses it.

I have shown the roll engaging device in the drawings as consisting of a belt which is held in position by suitable engaging devices. In the construction shown, there is an engaging device 7 at the bottom and an engaging device 8 at the top and the intermediate engaging devices 9 and 10. The roll engaging device in the particular construction illustrated, is shown as a belt and it may be a running belt or a stationary device. If it is a running device, the engaging devices 7 and 8, 9 and 10 are suitable direction changing devices, preferably pulleys or rollers. The device may be driven from any suitable source of power, such as the machine to

which the paper is delivered or to some separate source. A simple manner of driving the device is to drive the shaft 11 which carries the pulley 8. This shaft is shown as being provided with a beveled gear 12 which engages a beveled gear 13 on a shaft 14 driven by a belt 15 connected with a suitable source of power.

A weight 16 is connected with a direction changing device 17 which engages the paper engaging device 6. Some suitable means is provided for rotating the roll supporting device so as to bring the rolls successively into operative position with relation to the roll engaging device 6. The parts 7 and 8 are

preferably arranged so as to give a large contact area between the roll and the roll engaging device 6 and the weight 16 keeps the roll engaging device taut so as to secure the proper frictional contact.

In the construction illustrated, the new roll of paper is brought up to speed by engagement with the web 18 of the roll from which paper is being delivered to the device which uses it and the apparatus is so arranged that this new roll may be brought up to the desired speed while the apparatus is running at high speed and the web of the new roll connected with the web of the expiring roll at this high speed. The means for securing this in the particular construction illustrated is as follows:

The arms with which the rolls of paper are connected are provided with spindles 19 which engage such rolls by engaging the hollow core 30 thereof (see Fig. 4). These spindles are rotatably mounted upon the arms 2 as shown in Fig. 4. Some means is provided for holding the new roll so that it will not start rotating until it has been moved into sufficient contact with the web of the expiring roll to cause the roll engaging device 6 to exert a sufficient pressure to bring the new roll up to the proper high speed in a single revolution. This is accomplished in the construction shown by connecting to one or both of the spindles 19 of each roll, a suitable holding and releasing device which holds the roll against rotation until the force acting on it through the agency of the web of the expiring roll and the pressure of the roll engaging device is sufficient to give it the rate of acceleration necessary for the proper functioning of the device.

This holding and releasing device consists of a member 20 attached to the spindle 19 in any desired manner so as to rotate therewith. It may be integral with the spindle or may be suitably connected therewith. In the drawings, it is shown as separate from the spindle and connected therewith by fastening devices 21. The member 20 is provided with one or more notches 22. A holding and releasing member 23 has a part which projects into one of these notches when the roll is being held. The member 23 is shown as rocking about a pivot 24. The member 23 is preferably provided with rollers 25 and 26 at the opposite ends thereof. The pivot 24 is held in position by the supporting piece 27 attached to the plate 28 by the fastening pieces 29 and 30. When the member 25 is in engagement with the member 20, the roller 26 is in engagement with the stop 31, (see Fig. 5). This stop is connected with a sliding member 32 mounted in guides 33, 34.

To release the holding and releasing member 23, the stop 31 must be moved toward the guide 34. This movement of the stop is resisted by some suitable resisting device such

as the spring 35. The sliding member 32 is preferably provided with hand pieces 36 and 37 by which it may be easily moved. The member 23 is provided with a spring 38 which is connected at one end to a fixed part such as the support 29 and at the other end to the member 23 and is arranged to move the member 23, when released, back into its locking position that is with its end in the slot 22. The stop 31 is preferably provided with a beveled face 39. When the roll from which paper is being supplied is about exhausted, the roll support consisting of the shaft 1 and the arms 2, is moved in the direction of the arrow shown in Fig. 2 so as to move the new roll 4 into contact with the web 18 of the expiring roll 3 and as this movement is continued, the web 18 and the roll engaging device 6 exerts an increasing pressure on the new roll but the new roll is held against rotation by the engaging and releasing member 23 in the notch 22.

When the new roll 4 which has an adhesive 40 attached to the end of the web thereof (see Fig. 2), has been moved a sufficient amount so that a sufficient pressure is applied to it to give it the proper speed in one rotation, the holding and releasing device 23 is released and the roll is then set in motion responsive to the engagement therewith with the web 18. The adhesive 40 is preferably placed so that the roll may be given substantially a complete rotation before the adhesive comes in contact with the web 18. If the release of the roll 4 has been delayed until sufficient pressure has been applied to it, the speed of the web of this roll 4, when the adhesive reaches the web 18 of the expiring roll, will be substantially the same as the web 18 and the web of the roll 4 will then be automatically attached to the web 18.

The web 18 of the roll 3 is then broken and the delivery of the paper will then proceed from the new roll 4. It will be seen that by means of this construction the web of the two rolls may be connected together while the printing press or other machine is being run at a high speed, that is, this construction will make a high speed flying paster.

The releasing of the holding and releasing device 23 is regulated by the spring 35 which has an adjusting device 41 consisting of a nut threaded on the sliding member 32 so that the pressure exerted by it may be regulated. When the member 23 has one end in the notch 22 and the other end against the stop 31, it can only be released by moving the member 32 and the stop 31 in the direction of the guide 34 and the amount of pressure on the roll required to do this is regulated by the spring 35.

When a sufficient pressure is being exerted on the roll 4 by this contact with the web 18 and the pressure of the roll engaging device 6, the roller 26 will exert a sufficient pressure

on the stop 31 to move it. The member 20 will then exert a pressure on the roll 25 and the holding and releasing member 23 will be moved out of the notch 22. The roll 26 will 5 engage the beveled face 39 (see Fig. 5). The member 23 strikes the upstanding part 42 and is then held in the position shown in full lines in Fig. 5 out of contact with the member 20.

10 When it is desired to move the member 23 to its locking position, the sliding member 32 is moved so as to permit the roller 23 to move back of the stop 31 to the position shown in dotted lines in Fig. 5. The retracting spring 15 38 will cause this movement when the stop is moved to the proper position. The device is then ready for operation, as hereinbefore described.

Any suitable means may be used for moving 20 the roll supporting device. As herein shown, this is accomplished by means of a motor 43 which is connected to the shaft 1 in any suitable manner. As herein shown, the motor is provided with the pinion 44 which 25 engages a gear 45 on the shaft 46 carrying the worm 47 which engages a worm gear 48 on the shaft 1.

It will be seen that when the motor is operated, the shaft 1 will be rotated so as to 30 move the rolls of paper successively into operative position as desired. The adhesive material on the new roll instead of being placed at the end of the web thereof, is preferably placed at a sufficient distance 35 from the end so that if there should be any sliding between the adhesive material and the web of the exhausted roll, the adhesive material will simply move along this end section of the new roll and none of it will be 40 exposed on the web of the exhausted roll.

I have described a particular construction embodying the invention with a view of making 45 its application clear but it is, of course, evident that the parts may be varied in many particulars without departing from the spirit of the invention as embodied in the claims hereto appended. I therefore, do not limit myself to the particular construction shown.

The use and operation of my invention are 50 as follows:

When the rolls of paper are placed in position and the device started up, the parts are in the position shown in Fig. 1. When the roll 3 is about exhausted, the motor 43 is operated 55 so as to move the roll 5 toward the web 18 of the roll 3. The roll 4 is so positioned that the adhesive material 40 is at a point where the roll may be moved substantially a complete revolution before such adhesive strikes the web 18. As the roll 4 is moved into contact with the web 18, which is being pulled into the machine with which it is being used, pressure is applied to the roll and a force is also applied to said roll 60 tending to rotate it. The holding and re-

leasing member 23 being now in the notch 22 holds the roll against rotation. As the roll is moved farther along, pressure is being applied to its face by the roll engaging member 16 pressing the web 18 against the new roll.

The parts are arranged so that when the pressure is sufficient to cause the roll 4 to be brought up to the proper speed by approximately one revolution, the holding and releasing member 23 is forced out of the notch 22 into the position shown in full lines in Fig. 5, and the force tending to rotate the roll 4 is then free to do so and this roll is rotated and brought up to speed in one revolution and the adhesive material 40 engaging the web 18 causes the web of the new roll 4 to become attached to the web of the exhausted roll 3, the delivery of the paper being then transferred to the roll 4. The paper from the roll 3 is severed at a point between the roll 4 and the roll 3 in any convenient manner as by means of the hand of the operator or the like.

Fig. 3 shows the new roll after it has been set in motion and just before the adhesive thereon engages the web 18 of the exhausted roll. The roll engaging member 6 may be run as a belt or may be stationary, its function being to press the web 18 of the exhausted roll with sufficient force against the new roll. A sufficient pressure may be applied to the roll 4 by the web of the exhausted roll alone where the web of paper is of sufficient strength, and in that case the roll engaging member 6 may be omitted. The rotation of the expiring roll may then be stopped in any suitable manner as by any ordinary brake applied to it.

I claim:—

1. A paper delivering device comprising a roll supporting device for a plurality of rolls of paper, a roll engaging member for engaging the roll from which paper is being delivered, means for moving said roll supporting device so that a second roll having adhesive on its face, will be moved against the web running from the first mentioned roll and pressing said web against said roll engaging device to secure an increasing pressure between the web of the expiring roll and the new roll, a holding device for holding said new roll against rotation and means for releasing said new roll when the pressure thereon reaches a predetermined amount so that said roll will be quickly speeded up and the part thereof containing adhesive, attached to the web of the expiring roll.

2. A paper delivering device comprising supports for two rolls of paper from one of which paper is being delivered, means for moving the new roll, having adhesive on the face thereof, so that it will be moved against the web of the expiring roll, means for exerting a pressure between the new roll and the

- web of the expiring roll, a holding device for holding the new roll against rotation and means for releasing said holding device, when the pressure between the new roll and the web of the expiring roll has reached a predetermined amount, so that the new roll will be rotated and the portion containing adhesive will be attached to the web of the expiring roll.
- 10 3. A paper delivering device comprising supports for a plurality of rolls of paper from one of which paper is being delivered to the device with which it is used, means for bringing a new roll having adhesive on the face thereof and the web of the roll from which the paper is being delivered, into contact so as to exert a pressure between the new roll and said web, means for positively holding the new roll against rotation during the first 15 part of said contact and means for releasing said new roll so that the movement of the web of the roll from which paper is being delivered will rotate the new roll and bring the adhesive on the new roll into contact with said web so as to connect the material of the new roll to said web.
4. A paper delivering device comprising means for supporting two rolls of paper from one of which paper is being delivered to the device in connection with which it is used, means for bringing the new roll having adhesive on the face thereof and the moving web of the roll from which paper is being delivered, into contact, a holding and releasing 20 member associated with said new roll and adapted to hold it against rotation in response to the force applied to it by said moving web, a releasing mechanism for releasing said holding and releasing member after the desired pressure has been applied to the new roll so as to permit the pressure applied by said moving web to rotate the new roll.
5. A paper delivering device comprising means for supporting a plurality of rolls of paper from one of which paper is being delivered to the device in connection with which it is used, a roll engaging device adapted to engage one of the rolls while the paper is being delivered, means for bringing a new 25 roll having adhesive on the face thereof, and the moving web of the roll from which paper is being delivered, into contact, a holding and releasing member, a part rotating with the roll engaged by said holding and releasing member so as to hold said new roll against rotation in response to the force applied to it, by said moving web, means responsive to the force applied to said new roll by said moving web for releasing said holding and 30 releasing member so as to permit the pressure applied by said moving web to rotate the new roll and bring the adhesive thereon into contact with said moving web so as to connect the paper of the new roll with the web of the expiring roll.
6. A paper delivering device comprising means for supporting a plurality of rolls of paper from one of which paper is being delivered to the device in connection with which it is used, a roll engaging device adapted to engage one of the rolls while the paper is being delivered, means for bringing a new roll having adhesive on the face thereof, and the moving web of the roll from which paper is being delivered, into contact, a holding and releasing member, a part rotating with the roll engaged by said holding and releasing member so as to hold said new roll against rotation in response to the force applied to it by said moving web, a stop engaging said holding and releasing member so as to maintain it in its holding position, said stop being movably mounted, a spring for holding said stop into contact with said holding and releasing member and which permits the stop to move when the pressure applied thereto by the holding and releasing member reaches a predetermined point whereby the new roll is released and is rotated by the moving web so as to bring the adhesive thereon in contact with the moving web and connect the paper of the new roll with said moving web.
7. A paper delivering device comprising a support for a roll from which paper is being delivered to the device in connection with which it is used, and a support for a new roll, means for bringing the new roll having adhesive on the face thereof and the moving web of the roll from which paper is being delivered, into contact, and for increasing the pressure between them, a retarding device for retarding the rotative action of the moving web on the new roll and means for rendering said retarding device inoperative when the pressure between the web and the roll reaches a predetermined point so as to permit the pressure applied by the moving web to rotate the new roll and bring the adhesive thereon into contact with said moving web so as to connect the paper of the new roll with the moving web.
- Signed at Chicago, county of Cook, and State of Illinois, this second day of March, 1929.
- JOHN B. KOHLER.
